UNITED STATES PATENT OFFICE

146,865

DESIGN FOR A BASSINET

William Maxwell, Hawthorne, Calif., assignor of
one-half to Robert L. Hankins

Application February 1, 1946, Serial No. 126,155

Term of patent 14 years

(Cl. D5—5)

To all whom it may concern:

I, William Maxwell, a citizen of the United States, residing at Hawthorne, in the county of Los Angeles, State of California, have invented a new, original, and ornamental Design for Bassinet, of which the following is a specification, reference being had to the accompanying drawing, forming a part thereof.

Fig. 1 is a side elevational view showing a new and novel design for a bassinet.

Fig. 2 is a top plan view.

Fig. 3 is an end elevational view looking at the right end of Fig. 1.

Fig. 4 is an end elevational view looking at the left end of Fig. 1.

Fig. 5 is a perspective view.

I claim:

The ornamental design for a bassinet, as shown.

WILLIAM MAXWELL.
